US0D1092471S

(12) **United States Design Patent** (10) **Patent No.:** **US D1,092,471 S**
(45) **Date of Patent:** **** Sep. 9, 2025**

(54) **NETWORK ATTACHED STORAGE**

(71) Applicant: **SHENZHEN ORICO TECHNOLOGIES CO., LTD.**, Shenzhen (CN)

(72) Inventors: **Yeyou Xu**, Shenzhen (CN); **Ziwen Deng**, Shenzhen (CN)

(73) Assignee: **SHENZHEN ORICO TECHNOLOGIES CO., LTD.**, Shenzhen (CN)

(**) Term: **15 Years**

(21) Appl. No.: **30/000,325**

(22) Filed: **Apr. 21, 2025**

Related U.S. Application Data

(62) Division of application No. 29/820,355, filed on Dec. 21, 2021.

(57) **CLAIM**

The ornamental design for a network attached storage, as shown and described.

DESCRIPTION

FIG. 1 is a front, left side and top perspective view of a network attached storage showing our new design; FIG. 2 is a rear, right side and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view taken from detail circle 9 in FIG. 1.

The dash-dash broken lines in the drawings depict the portions of the network attached storage that form no part of the claimed design.

The dot-dash broken lines in the drawings depict the boundaries of the enlarged views and form no part of the claimed design.

1 Claim, 9 Drawing Sheets
